United States Patent Office.

DAVID MATTHEW, OF PRAIRIE DU CHIEN, WISCONSIN.

Letters Patent No. 72,309, dated December 17, 1867.

IMPROVEMENT IN PROTECTING STEAM-BOILERS FROM CORROSION.

The Schedule referred to in these Letters Patent and making part of the same.

TO ALL WHOM IT MAY CONCERN:

Be it known that I, DAVID MATTHEW, of Prairie du Chien, in the county of Crawford, and State of Wisconsin, have invented a Device for Protecting Steam-Boilers from Corrosion; and I do hereby declare that the following is a full, clear, and exact description thereof, reference being had to the accompanying drawings, making a part of this specification, in which—

Figure 1 is a perspective view of a well-known form of steam-boiler, with a portion of its shell broken away to show the improved protecting-device within it.

Figure 2 is a view of the protecting-device, partly in section.

Figure 3 is a transverse section of fig. 2.

Similar letters of reference indicate corresponding parts in the three figures.

This invention relates to an improved device, which is designed for protecting the metal of which steam-boilers are constructed from rapid destruction, caused by the impurities of the water used in generating steam, and which I believe will also add to the purity and efficiency of the steam, as will be hereinafter described.

To enable others skilled in the art to understand my invention, I will describe its construction and operation:

In the accompanying drawings I have represented one mode of constructing and applying the improved galvanic protectors, but I do not confine my invention to the precise construction of the device shown, as it may be modified, both in form and construction, without departing from the principle of my invention; nor do I wish to be understood as making claim to a method of protecting boilers set forth in the patent numbered 30,511, nor to the plans set forth in the patents numbered 34,455 and 64,992.

The nature of my invention consists in the employment within steam-boilers of one or more devices, composed of a series of disks or plates of copper and zinc, or other equivalent metals, applied upon a rod which is pointed at its ends or poles, and supported by lead or other suitable plates, which rest upon the shell of the boiler, and sustain the copper and zinc pile, so as to allow a free circulation of water beneath it.

In the accompanying drawings, fig. 2, *a a* represent a series of copper-disks, of any suitable thickness and diameter, and having holes through their centres. *b b* represent a series of zinc disks, which may be equal in diameter to the copper disks *a*, but much thicker than the latter. These disks are arranged in a pile, so that the copper and zinc will alternate, as shown, and a copper rod, *c*, is passed through them, the extremities of which are pointed and screw-cut, as shown. The ends of the pile of copper and zinc plates terminate in some comparatively soft metal plates or disks, *d d*, of greater diameter than the intermediate disks. These heads or end pieces are bored through centrally, and slipped upon the ends of the rod *c*, after which nuts *e e* are applied upon the latter, and the whole screwed tightly together, forming what I shall denominate a galvanic pile.

It is obvious that the piles may be made of other metals than those above mentioned, which are chiefly electro-positive to the metal of which the boiler-shell is composed; and said piles may be made of any suitable length and any desired number of plates.

Having described my invention, what I claim as new, and desire to secure by Letters Patent, is—

A galvanic pile, which is composed of copper and zinc plates, or other metals equivalent in galvanic properties, applied upon a metal rod, which is provided on its ends with supporting-disks, said pile being employed substantially in the manner and for the purposes described.

DAVID MATTHEW.
